UNITED STATES PATENT OFFICE.

LOUIS J. RIEGLER, OF BEN AVON, PENNSYLVANIA.

METALLIC TIE.

1,043,727.

Specification of Letters Patent.

Patented Nov. 5, 1912.

Application filed February 3, 1912. Serial No. 675,319.

To all whom it may concern:

Be it known that I, LOUIS J. RIEGLER, a resident of Ben Avon, in the county of Allegheny and State of Pennsylvania, have invented a new and useful Improvement in Metallic Ties; and I do hereby declare the following to be a full, clear, and exact description thereof.

My invention relates to metallic railway ties, and has special reference to such ties which are of substantially I-beam section or shape, as well as other sections or shapes.

Heretofore, with metal ties of the I-beam type or section, as shown in Figure 5, the tamping has all been done against the bottom surface of the bottom flange and the ties lie on the tamped surface without being embedded in the ballast, so that the tie can easily be moved forward or back, as the thin edge of the bottom flange easily shears through the ballast, and even though the ballast is filled in between the ties and level with their tops the resistance to movement is only slightly increased because the ballast so disposed is forced upward and resists movement of the tie only by its weight by reason of there being nothing against which it can abut. The ballast is therefore easily dislodged. To bend the edges of the bottom flange of the tie down as has been done in some cases adds nothing to the stability of the tie as regards its embedding qualities, as the action is the same as above, but it greatly increases the difficulty of tamping. Other designs of metal ties with sharp corners at the bottom flange or even sawed wood ties are subject to the same objections, *i. e.*, their stability is limited to the weight of the ballast above the lower edge of the tie and to the friction between the bottom surface of the tie and the ballast. The slew-ing of ties has the effect of tightening the gage and throwing the track out of line, and slewed ties slip off the ballast that has been tamped onto untamped ballast and thereby materially affect the surface of the track, causing it to become rough and uneven, to increase the track labor necessary to proper maintenance and tending toward a decrease in the life of track material.

All double track and some single track has a tendency to creep, and the prevention of creeping is accomplished by anchoring the rails to the ties through splice bars and by other devices, so that it is necessary that the ties themselves be anchored or embedded

in the ballast in order that they may be able to restrain the movement of the rails, or otherwise the cost and difficulty of maintaining the track will be greatly increased. 60

One of the important functions of cross-ties is to transmit the loads imposed upon them to the ballast, through which they are carried to the sub-grade, and with the present form of track construction flat bottomed ties with sharp corners transmit the pressure nearly vertically through the ballast to the sub-grade so that the pressure is not distributed uniformly on the sub-grade, the unit pressure near the middle of the ties is 65 much greater than at the edges of the ties, and this unit pressure decreases in the spaces between the ties. With present day practice in tie spacing and ballast depth there is a space midway between the ties that carries 70 no load whatever, the entire load being carried by the sub-grade immediately under and for a short distance on each side of the ties. This unequal distribution results in depressing the sub-grade under the ties, which 75 forces it up in the spaces between the ties and causes it to mix with the ballast. This is further aggravated by water collecting in such depressions, which will soften the sub-grade at that point and thereby make it all 80 the more liable to be further depressed. The results are increased labor necessary to properly maintain the tracks.

The unequal unit pressure can be made more nearly uniform by increasing the number of ties or by increasing the depth of the ballast, but both methods are costly and unsatisfactory. The first method means increased cost for ties and more difficulty in tamping, while the second method is extravagant, as a very large increase in the volume of ballast results in only a small reduction of unit pressure. 90

The object of my invention is to overcome these difficulties and objections and to 100 so form the ties that they will be prevented from slew-ing, will be anchored securely in the ballast, and will more uniformly distribute the loads to the sub-grade.

To these ends my invention consists, generally stated, in the novel form and construction of a metallic railway tie, as herein-after more specifically set forth and particularly pointed out in the claims. 105

To enable others skilled in the art to 110 which my invention appertains to construct and use my improved metallic railway tie,

I will describe the same more fully, referring to the accompanying drawing, in which—

Fig. 1 is a side elevation of a portion of a railroad track showing my improved ties applied thereto. Fig. 2 is a side view of one of the ties. Fig. 3 is a top plan view of the same. Fig. 5 is an enlarged cross-section of the tie. Fig. 4 is a side elevation 10 of a track having ordinary I-beams for ties.

Like symbols of reference herein indicate like parts in each of the figures of the drawing.

As illustrated in the drawing, *a* represents 15 ballast resting on the sub-grade *b*, and *1* is my improved metallic railway tie resting upon said ballast and carrying the rails *c* of the tracks secured across the same in the usual approved manner.

20 The tie *1* being substantially an I-beam section or structure is provided with the top bearing plate *2*, upon which the track rails *c* rest and are secured, and such plate is formed by two horizontal flange portions *3*, 25 each of which extends out from the top of and on each side of the vertical web *4* of the tie connected to said plate. Connected to the bottom of the web *4* is the bottom or base plate *5* for resting on the ballast *a*, and 30 the bottom face of said plate is adapted to have said ballast conform thereto, said plate being formed of two flanges *6*, each of which extends out from each side of said web *4*. These flanges *6* are curved upwardly 35 and the convex bottom face in forming the base plate *5* and said flanges can be formed on any desired radius, while the upper faces of such flanges are also curved upwardly from the web *4* and preferably on a greater 40 radius than that of the bottom face of the same in order to make such flanges slightly tapered toward their rounded outer edges 7.

The entire tie is rolled from a single or one piece of metal in the usual manner with 45 the flanges *6* formed in a horizontal position, and afterward the flanges *6* are curved up by the rolling or other processes from such horizontal positions in the usual manner.

50 It will thus be seen that when my improved metallic railway tie is in position in the track the pressure is transmitted to the ballast normally to the curved sides of the bottom plate on the tie, and such pressure is thereby spread out over a greater area of the sub-grade, thus reducing the unit pressure and causing a more uniform distribution by reason of such curved sides acting as a wedge on said ballast. The 55 curved bottom face of the ties and curved up extensions or flanges on said face will also prevent slewing of the ties, will more securely anchor them in the ballast, as well as greatly facilitate the tamping of the ties, 60 and at the same time to cause the ties to be 65

embedded properly. The ties cannot be moved forward or backward, as to do so it is necessary that the ballast be forced down against the sub-grade, and as the ballast is supported by the sub-grade it, therefore, 70 cannot be dislodged.

Various other modifications and changes in the design and construction of my improved metallic railway tie may be resorted to without departing from the spirit of the 75 invention or sacrificing any of its advantages.

What I claim as my invention and desire to secure by Letters-Patent is—

1. A metallic railway tie having a single 80 vertical web and a base plate connected thereto, said base plate having a single continuous upwardly curved bottom surface.

2. A metallic railway tie having a single 85 vertical web and a base plate connected thereto, said base plate having a single continuous bottom surface and being concave to said web.

3. A metallic railway tie having a single 90 vertical web and a base plate connected thereto, said base plate having a single continuous upwardly curved bottom surface, and having the side edges thereof upwardly curved therefrom.

4. A metallic railway tie having a single 95 vertical web and a base plate connected thereto, said base plate having a single continuous bottom surface and being concave to said web, and having the side edges thereof upwardly curved therefrom.

5. A metallic railway tie having a single 100 vertical web and a base plate connected thereto at its center, said base plate having a single continuous upwardly curved bottom surface.

6. A metallic railway tie having a single 105 vertical web, and a base plate connected thereto at its center, said base plate having a single continuous bottom surface and being concave to said web.

7. A metallic railway tie having a single 110 vertical web, and a base plate connected thereto at its center, said base plate having a single continuous upwardly curved bottom surface, and having the side edges there- 115 of upwardly curved therefrom.

8. A metallic railway tie having a single 120 vertical web, and a base plate connected thereto at its center, said base plate having a single continuous bottom surface and being concave to said web, and having the side edges thereof upwardly curved therefrom.

9. A metallic railway tie having a single 125 vertical web, a bearing plate connected thereto at its upper edge, and a base plate connected to said web at its lower edge, said base plate having a single continuous upwardly curved bottom surface.

10. A metallic railway tie having a single 130 vertical web, a bearing plate connected

- thereto at its upper edge, and a base plate connected to said web at its lower edge, said base plate having a single continuous bottom surface and being concave to said web.
- 5 11. A metallic railway tie having a single vertical web, a bearing plate connected thereto at its upper edge, and a base plate connected to said web at its lower edge, said base plate having a single continuous
- 10 upwardly curved bottom surface and having the side edges thereof upwardly curved therefrom.
12. A metallic railway tie having a single

vertical web, a bearing plate connected thereto at its upper edge, and a base plate 15 connected to said web at its lower edge, said base plate having a single continuous bottom surface and being concave to said web and having the side edges thereof upwardly curved therefrom.

20 In testimony whereof, I, the said LOUIS J. RIEGLER, have hereunto set my hand.

LOUIS J. RIEGLER.
